COMBINED BOUDOIR CABINET AND LAMP

Steve Cannella, New York, N. Y.

Application February 20, 1952, Serial No. 18,609

Term of patent 14 years

(Cl. D48—20)

To all whom it may concern:

Be it known that I, Steve Cannella, a citizen of the United States, residing at New York, in the Borough of Manhattan and State of New York, have invented a new, original, and ornamental Design for Combined Boudoir Cabinet and Lamp, of which the following is a specification, reference being had to the accompanying drawing, forming a part hereof.

Fig. 1 is a side elevational view of a combined boudoir cabinet and lamp showing my new design;

Fig. 2 is a top plan view; and

Figs. 3 and 4 are transverse sectional views taken respectively on the lines 3—3 and 4—4 of Fig. 1.

I claim:

The ornamental design for a combined boudoir cabinet and lamp, as shown.

STEVE CANNELLA.
